INDUCTION APPARATUS

Carl Gustaf Samuel Lindblom, Stockholm, Sweden, assignor to Svenska Ackumulator Aktiebolaget Jungner, Stockholm, Sweden

Application March 24, 1939, Serial No. 264,010
In Sweden June 20, 1936

7 Claims. (Cl. 175—364)

The present invention relates to induction apparatus, for instance for illuminating devices, in which the source of current is connected to the primary winding of the induction apparatus over 5 contacts controlled by the hammer armature of the apparatus and in which a discharge tube, for instance a neon tube or the like, is connected to the secondary winding of the apparatus.

At the relative high primary strengths of current, which generally are used, it has been proved that, also when using the best materials in the contacts controlled by the hammer armature, a transfer of metal takes place from the positive contact to the negative one. Through such a 10 metal transfer a crater will be formed in the positive contact, whereas a pike will be formed on the negative contact. Within a shorter or longer time, depending on the current density, the said pike grows larger, and flakes are formed, 15 which cause a short-circuiting of the contacts, so that the induction apparatus and, as a consequence, the devices operated by the same are wholly put out of function.

The present invention has for its object to avoid 20 the above mentioned drawback and consists substantially in this that a pole reversing switch is placed in the primary circuit of the induction apparatus. Preferably, the said reversing switch may be combined with or made as a circuit 25 breaking switch and so constructed that, after a circuit breaking has taken place, a returning movement to the foregoing switch on position cannot be effected. The reversing switch can be arranged to be operated manually 30 or automatically, for instance by means of a clock-work or the like, which effects the required pole-reversing at desired intervals.

In the annexed drawing an embodiment of a device according to the invention is shown diagrammatically. Fig. 1 illustrates a reversing switch made as a rotary circuit breaker and an induction apparatus connected thereto. Fig. 2 is a top view of an associated primary source of current in the form of a storage battery.

Referring to Fig. 1, 1 and 2 designate two circular contact bars relating to the reversing switch, the one 1 of which is connected to the one end of the primary winding 4 of the induction apparatus by means of a wire 3, whereas the 45 second bar 2 in the ordinary way is interruptedly connected to the other end of the said primary winding through a wire 5 and over the contacts 7 and 8 controlled by the hammer-armature 6. Connected to the secondary winding 9 of the 50 induction apparatus is a neon tube 10 or the like.

Sliding against the contact bars 1 and 2 are the outer ends of two mutually electrically insulated contact springs 11 and 12, respectively, which are secured to a central rotary shaft 13. The inner ends of the contact springs 11, 12 can be moved 5 into contact with stationary pairs of contacts 14a, 15a, 14b, 15b, 14c, 15c and 14d, 15d, respectively, arranged in groups, the contacts 14a—14d of which on the one hand and the contacts 15a—15d on the other hand are alternately connected 10 to the negative pole and the positive pole, respectively, of the battery 20 through wires 16, 17, 18 and 19.

Firmly secured to the shaft 13 of the switch is a ratchet wheel 21 meshing with a stationary 15 spring pawl 22, which permits rotation of the shaft and the springs 11 and 12 and also of the ratchet wheel 21 in the clock-wise direction, but prevents rotation in the opposite direction.

In the position denoted by II in Fig. 1, in 20 which the inner ends of the contact springs 11, 12 are into contact with the corresponding pair of contacts 15a, 14a, the contact 8 of the induction apparatus is connected to the negative pole of the battery 20 over the wire 5, the contact 25 bar 2, the spring 12, the contact 14a and the wires 16 and 18, whereas the contact 7 of the armature 6 is connected to the positive pole of the battery over the primary winding 4, the wire 3, the contact bar 1, the spring 11, the contact 30 15a and the wires 17 and 19.

When rotating the contact springs 11, 12 to the position III—III a circuit breaking occurs, and when further rotating the springs to the position IV the contact 8 of the induction apparatus will be connected to the positive pole of the battery 20 over the wire 5, the contact bar 2, the spring 12, the contact 14b and the wires 17 35 and 19, whereas the armature contact 7 will be connected to the negative pole over the primary 40 winding 4, the wire 3, the contact bar 1, the spring 11, the contact 15b and the wires 16 and 18. Thus, a pole reversing has been effected.

When further rotating the contact springs 11, 12 in the direction mentioned, firstly a circuit 45 breaking takes place in the position I—I and then again a pole reversing in the position V over the contacts 14c and 15c. In the following position III—III a circuit breaking will again take place, and in the position VI a pole reversing 50 again is effected over the contacts 14d and 15d.

Through the said reversing, which may be effected manually or automatically at intervals, as mentioned, the described deformation of the contacts 7 and 8 will be effectively prevented, 55

and the operation of the induction apparatus will be undisturbed. Further, the pawl and ratchet means 22, 21 positively prevents the contact springs 11, 12 from being moved back into a foregoing position after a circuit breaking having been effected.

At an exchange of battery it may happen that at the connection of the new battery a pole reversing may be made, for instance through inadvertency. Thus, the result will be that at the consecutive adjustment of the reversing switch into the new switch-on position no pole reversing will take place with respect to the contacts 7, 8 and that consequently the said contacts will have to work with the same pole connections during two periods, which can be disadvantageous, particularly in case of the said periods being long.

In order to avoid the said drawback an arrangement according to Fig. 2 can be made. In the said figure, 20 denotes the battery as is the case in Fig. 1. The separate cells are placed in a casing 23. The contact bars of the terminals of the battery are denoted by 24 and 25, respectively, and the first mentioned bar 24 adapted to be connected to the positive terminal of the battery is made so long, as to project outside the battery casing. As a consequence, in order that the said bar may be connected to the corresponding terminal, a recess 26 must be made in the associated wall of the battery casing. The negative bar 25 is so short that it can be connected to its terminal without any corresponding recess being made in the wall of the casing. Evidently, it is possible to apply the last mentioned bar 25 to the positive terminal, but on the other hand the bar 24 cannot be applied to the negative terminal. As a consequence, there is no risk for a pole reversing at an exchange of battery. For the same purpose the battery terminals may be made of different thickness, and the bars 24, 25 may be provided with corresponding holes of different sizes, so that a confusion cannot be made.

What I claim as new and desire to secure by Letters Patent of the United States of America is:

- 45 1. In combination, an induction apparatus comprising a primary winding, a secondary winding, an oscillatory armature operated by said primary winding, and contacts in the circuit of said latter winding controlled by said armature upon the oscillations thereof, a pole reversing switch in the circuit of said primary winding, and means permitting movements of said switch in the one direction only.
- 50 2. In combination, an induction apparatus comprising a primary winding, a secondary winding, an oscillatory armature operated by said primary winding, and contacts in the circuit of said latter winding controlled by said armature

upon the oscillations thereof, a pole reversing switch in the circuit of said primary winding, and means for temporary breaking said circuit when effecting said pole reversing.

3. In combination, an induction apparatus 5 comprising a primary winding, a secondary winding, an oscillatory armature operated by said primary winding, and contacts in the circuit of said latter winding controlled by said armature upon the oscillations thereof, a combined pole reversing and circuit breaking switch in the circuit of said primary winding, and means permitting movements of said switch in the one direction only.

4. In combination, an induction apparatus 15 comprising a primary winding, a secondary winding, an oscillatory armature operated by said primary winding, and contacts in the circuit of said latter winding controlled by said armature upon the oscillations thereof, a pole reversing 20 switch in the circuit of said primary winding, means for temporary breaking said circuit when effecting said pole reversing, and means for preventing a return movement of said pole reversing switch into a foregoing position after the circuit 25 breaking having taken place.

5. In combination, an induction apparatus comprising a primary winding, a secondary winding, an oscillatory armature operated by said primary winding, and contacts in the circuit of 30 said latter winding controlled by said armature upon the oscillations thereof, a combined rotary pole reversing and circuit breaking switch in the circuit of said primary winding, and means permitting rotation of said switch in the one direction only. 35

6. In combination, an induction apparatus comprising a primary winding, a secondary winding, an oscillatory armature operated by said primary winding, and contacts in the circuit of 40 said latter winding controlled by said armature upon the oscillations thereof, a rotary pole reversing switch in the circuit of said primary winding, and means permitting rotation of said switch in the one direction only. 45

7. In combination, an induction apparatus comprising a primary winding, a secondary winding, an oscillatory armature operated by said primary winding, and contacts in the circuit of said latter winding controlled by said armature 50 upon the oscillations thereof, a direct current source in connection with said primary winding, differently shaped terminal connections for said source, a pole reversing switch in the circuit of said primary winding, and means permitting movements of said switch in the one direction only. 55

CARL GUSTAF SAMUEL LINDBLOM.
